UNITED STATES PATENT OFFICE.

LOUIS G. CARON, OF TORONTO, ONTARIO, CANADA.

ARTIFICIAL HAND.

1,285,617.

Specification of Letters Patent. Patented Nov. 26, 1918.

Application filed February 2, 1918. Serial No. 215,194.

To all whom it may concern:

Be it known that I, LOUIS G. CARON, of the city of Toronto, in the county of York, Province of Ontario, Canada, a citizen of the United States of America, have invented 5 certain new and useful Improvements in Artificial Hands, of which the following is a specification.

This invention relates to artificial hands 10 of the type in which it is desired that the digits shall be capable of being flexed substantially to resemble the movements of the natural hand, and my object is to devise simple means for flexing and extending the 15 digits and for releasably locking the fingers in flexed position.

I attain my object by means of the constructions hereinafter more specifically described and illustrated in the accompanying 20 drawings in which—

Figure 1 is a front elevation, partly in section, of a hand constructed in accordance with my invention;

Fig. 2 a side elevation of the same partly 25 in section; and

Fig. 3 a longitudinal section showing more particularly the hook pivoted in opposition to the fingers.

In the drawings like numerals of reference 30 indicate corresponding parts in the different figures.

1 is the hand. The wrist portion of the hand is formed as a hollow ball member 2 whereby it may be connected with a wrist 35 member such as shown in my co-pending application No. 207335 filed December 15th, 1917.

The thumb 3 is pivoted at 4 to swing on an axis transverse of the palm of the hand 40 whereby the thumb moves in opposition to the fingers. Its inner end is provided with a ratchet rack 5, which is engaged by a spring actuated dog 6 suitably fulcrumed within the hand and extending out through 45 a suitable opening or slot in the hand. A coil spring 7 is located on the pivot pin of the thumb and is provided with arms, one of which engages the thumb and the other a suitable stationary part 8. This spring 50 tends to move the thumb away from the fingers.

The fingers are provided with first, second and third joints. The first joints or knuckle members 9 are rigidly connected together 55 and are pivoted on the hand by means of a pivot pin 10. The second and third joints

11 and 12 are independently pivoted as shown. The connected first joints are provided with a worm wheel 13 with which meshes a worm 14 journaled within the hand. A coil-spring 15 is located on the journal of the worm and is provided with arms, one of which engages the worm and the other a suitable stationary part 16. This spring tends to rotate the worm to flex the united 65 first finger joints, that is, to bend them toward the thumb. To operate the second joints I provide for each finger a bell crank lever 17 pivoted on each first joint in front of the pivot pin 10. One arm of the bell 70 crank lever extends into the hand and has a sliding connection therewith. Preferably a slot 18 is formed in the arm of the bell crank lever which engages a pin 19 in the hand. The other end of each bell crank lever 75 extends rearwardly and is pivotally connected with one end of a link 20 pivotally connected with the second finger joint in front of the pivot thereof. From the construction described it follows that when the first finger 80 joints are rocked, each of the bell crank levers 17 is also rocked so that its end moves closer to the pivot pin 10. The links 20 are thus drawn upon and each second finger joint is flexed. 85

If the third finger joints are also pivoted, as is preferably the case, a rearwardly extending arm 21 is formed on each link 20. Each of these arms is pivotally connected with a link 22, the other end of which is 90 connected with the third finger joint at the front of its pivot. By partially rotating the worm 14, the fingers may thus be extended as shown in full lines in Fig. 2 or flexed 95 as shown in dotted lines. The worm is partially rotated to extend the fingers through the medium of a cable 31, which may be connected with any suitable operating means as well known in the art.

For my purposes it is desirable that the 100 ends of the forefinger and thumb should co-operate in grasping an object, while at other times it may be necessary for the end of the thumb to pass the forefinger. I therefore hinge the end 23 of the thumb at 24 on the 105 main part of the thumb. Co-acting shoulders 25 are formed on the parts of the thumb which prevent the end swinging too far in either direction.

As in the construction shown in the prior 110 application hereinbefore referred to, I prefer to employ in the present hand a hook 26

- which is located at the opposite side of the palm of the hand to the thumb. This hook works through a slot formed in the palm of the hand so that it may be either swung up 5 to the position shown in dotted lines in Fig. 3 or, when not required, swung down out of the way as shown in full lines. This hook is provided with a ratchet rack 27 concentric with its pivot or hinge pin 19 and with this 10 rack engages a spring actuated dog 29, which dog has an arm 30 extending out through a hole or slot in the hand, by means of which it may be disengaged from the rack when necessary.
- 15 From the above description and drawings it will be seen that I have devised finger-operating mechanism which is extremely simple and not liable to get out of order. It further possesses the advantage that, 20 though moved to the flexed position by a spring, the fingers will be locked in the flexed position through the medium of the worm and worm wheel until such time as the worm wheel is actuated to extend them.
- 25 Perfect coöperation between the fingers and thumb and hook will also be obtained so that any desired objects may be securely grasped.
- What I claim as my invention is:—
- 30 1. In an artificial hand, the combination of a finger joint pivotally connected thereto; a bell-crank lever pivoted on the joint in front of the pivot thereof; a second finger joint pivoted on the first; a link pivotally connected at one end to said second joint in front of its pivot and at its other end to the adjacent end of the bell crank lever, the other end of the lever having a sliding connection with the hand; and means for rock- 35 ing the first joint on its pivot.
- 40 2. In an artificial hand, the combination of a finger joint pivotally connected thereto; a bell crank lever pivoted on the joint in front of the pivot thereof; a second finger joint pivoted on the first; a link pivotally connected at one end to said second joint in front of its pivot and at its other end to the adjacent end of the bell crank lever, the other end of the lever having a sliding connection with the hand; and means for rock- 45 ing the first joint on its pivot.
- 45 3. In an artificial hand, the combination of a finger joint pivotally connected thereto; a bell crank lever pivoted on the joint in front of the pivot thereof; a second finger joint pivoted on the first; a link pivotally connected at one end to said second joint in front of its pivot and at its other end to the adjacent end of the bell crank lever, the other end of the lever having a sliding connection with the hand; a third joint pivoted 50 on the second; a link pivotally connected at one end to said joint; a rearwardly extending arm on the first mentioned link to which the other end of the second mentioned link is pivotally connected; and means for rock- 55 ing the first joint on its pivot.
3. In an artificial hand, the combination of a finger joint pivotally connected thereto; a bell crank lever pivoted on the joint in front of the pivot thereof; a second finger joint pivoted on the first; a link pivotally connected at one end to said second joint in front of its pivot and at its other end to the adjacent end of the bell crank lever, the other end of the lever having a sliding connection with the hand; and means for rock- 60 ing the first joint on its pivot comprising a worm wheel formed on the first finger joint; a worm journaled in the hand and meshing with the worm wheel.
4. In an artificial hand, the combination of a finger joint pivotally connected thereto; a bell crank lever pivoted on the joint in front of the pivot thereof; a second finger joint pivoted on the first; a link pivotally connected at one end to said second joint in front of its pivot and at its other end to the adjacent end of the bell crank lever, the other end of the lever having a sliding connection with the hand; and means for rock- 65 ing the first joint on its pivot comprising a worm wheel formed on the first finger joint; a worm journaled in the hand and meshing with the worm wheel.
4. In an artificial hand, the combination of a finger joint pivotally connected thereto; a bell crank lever pivoted on the joint in front of the pivot thereof; a second finger joint pivoted on the first; a link pivotally connected at one end to said second joint in front of its pivot and at its other end to the adjacent end of the bell crank lever, the other end of the lever having a sliding connection with the hand; and means for rock- 70 ing the first joint on its pivot comprising a worm wheel formed on the first finger joint; a worm journaled in the hand and meshing with the worm wheel.
5. In an artificial hand, the combination of a first finger joint pivotally connected thereto; a worm wheel for actuating said joint concentric with the pivot thereof; a worm journaled in the hand and meshing with the worm wheel; a second finger joint pivoted on the first; and means whereby the rocking of the first finger joint on its pivot rocks the second in the same direction.

Signed at Toronto, Canada, this 23rd day 95 of January, 1918.

LOUIS G. CARON.
